UNITED STATES PATENT OFFICE

LOUIS H. DEBAENE, OF PHILADELPHIA, PENNSYLVANIA

LACE MACHINE

Application filed October 27, 1927. Serial No. 229,078.

This invention relates to a multiple bar attachment for lace machines and has for an object to provide a connection between the lace machine and the jacquard adapted to control the operation of the machine whereby to permit an increase in the number of gaits possible to be worked by the jacquard.

A further object is to provide an attachment of this character which may be interposed in operative position between a levers lace machine and the conventional type of jacquard employed in connection therewith, without necessitating any changes in the construction of either the machine or the jacquard, which is simple and practical in construction, efficient and reliable in performance, inexpensive to manufacture and install and otherwise well adapted for the purposes for which the same is intended.

Other objects and advantages reside in the special construction, combination and arrangement of the various elements forming the invention as more fully hereinafter described and claimed, reference being had to the accompanying drawings forming part hereof, wherein like numerals refer to like parts throughout the specifications and in which

Figure 1 is a top plan view of my attachment shown in operative position with respect to the lace machine and jacquard,

Figure 2 is a bottom plan view of the rod control means for the drum,

Figure 3 is a view in side elevational view, and

Figure 4 is a sectional view taken substantially along a line 4-4 of Figure 1.

Referring now to the drawings in detail, the invention is mounted in operative position upon a pair of longitudinal frame members 5 having one end attached to the lace machine 6 and the opposite end suitably secured adjacent the jacquard 7. Intermediate the ends of the frame members 5 is arranged a transverse frame member 8 having a support 9 extending therefrom which forms a mounting for a shaft 10 on which a drum 11 and cog-wheel 12 are rotatably mounted, the drum and cog-wheel being secured to each other for uniform movement.

In place of the ordinary bar which usually extends between the lace machine and the jacquard and which is operated through the usual dropper boxes carried by the jacquard for working the machine the usual number of gaits, I provide a flexible bar 13 having one end extending in a direction toward the lace machine 6 and arranged in operative association therewith in a manner well understood in the art, and its opposite end wound about the drum 11 and secured thereto. A working arm 15 is connected to one of the dropper boxes on the jacquard and operated by the dropper in the same manner as the ordinary bar as heretofore provided. The opposite end of the arm 15 is provided with a set of teeth 16 in the form of a rack bar and engageable with the teeth of the cog-wheel 12 whereby through the operation of the arm 15 the cog-wheel 12 is rotated so as to move the bar 13.

After the arm 15 has been operated to its fullest extent, the cog-wheel is secured by a stop 17 which is also connected at one end to a dropper box on the jacquard with its opposite end provided with a rack segment 18 for engaging the cog-wheel and securing the same against movement. The stop 17 is supported on the shaft 10 through a slotted opening 19 so that upon the operation of the stop by the jacquard the segment 18 is engaged with the cog-wheel 12 to prevent the same from moving in either direction. A release rod 20 extends longitudinally in spaced parallel relation between the arm 15 and stop 17 with one end similarly connected to a dropper box on the jacquard and its opposite end pivotally connected by a pin 21 to links 22 and 23 connected respectively to the arm 15 and stop 17.

Coil springs 24 are attached respectively to the arm 15, stop 17 and release rod 20 and connect the same with the transverse member 8 whereby to normally move the same in a direction away from the jacquard and disengage the segment 18 from the cog-wheel 12. In the operation of the device after the dropper box to which the arm 15 is attached has moved the cog-wheel 12 and the rod 13 to work the lace machine the usual number of

gaits, which in accordance with the standard type of machine is 31 gaits, the arm 15 will then secure the cog-wheel against movement until the stop 17 which is also worked by one of the dropper boxes of the jacquard has likewise been moved into engagement with the cog-wheel 12. The cog-wheel is thus held until the release rod 20 also operated through one of the dropper boxes has been moved to move the arm 15 from engagement with the cog-wheel, the spring 24 returning the arm 15 to its original position. The release rod 20 is then released from the jacquard to be returned to its original position by the spring 24 attached thereto which thereby moves the arm 15 into engaged position with the cog-wheel. After the jacquard has released the stop 17 which is returned to its neutral position by the spring 24 the attachment is then ready to repeat the operation for working an additional 31 gaits.

It is obvious that the invention is susceptible of various changes and modifications without departing from the spirit of the same or the scope of the appended claims, and I accordingly claim all such forms of the invention to which I am entitled.

I claim:

1. A control attachment interposed between a lace machine and its operating jacquard comprising a flexible bar, operating means therefor, means releasably retaining said bar and means attached to the jacquard for periodically releasing said bar retaining means.
2. In a control attachment interposed between a lace machine and its operating jacquard comprising an operating bar extending from the jacquard and operated thereby to the machine, a drum having one end of the bar secured thereto, a cog-wheel attached to the drum and arranged for rotation therewith, a working arm operatively connected to the jacquard of the machine, a stop, a release rod, said stop and said release rod being operatively connected to the jacquard, means for engaging said stop with the cog-wheel and means associated with the release rod for controlling the engagement or disengagement of the working arm and stop with the cog-wheel.

In testimony whereof I affix my signature.

LOUIS H. DEBAENE.
